(57) **CLAIM**

The ornamental design for a supporting plate for cleaning pad for robotic vacuum cleaner, as shown and described.

DESCRIPTION

1. Supporting plate for cleaning pad for robotic vacuum cleaner

1.1 : Front

1.2 : Back

1.3 : Left

1.4 : Right

1.5 : Top

1.6 : Bottom

1.7 : Perspective

Figs. 1.1-1.7 show our new design of a supporting plate for cleaning pad for robotic vacuum cleaner.

The broken lines shown in the drawings depict portions of the supporting plate for cleaning pad for robotic vacuum cleaner that form no part of the claimed design.
